The American Laundry Machinery Company,
Cincinnati, Ohio, a corporation of Ohio

Application November 8, 1930, Serial No. 494,269

9 Claims. (Cl. 68—9)

My invention relates to pressing machines and, particularly, to operating mechanism for a pressing machine including a work supporting bed and a head movable into cooperative relation to cause the pressing action.

In presses of this type, the pressing head is normally separated a sufficient distance from the work supporting bed so that work may be conveniently placed thereon or removed therefrom and with sufficient space between the pressing head and work supporting bed to permit clear visibility of the pressing bed or the work thereon when the bed and head are out of cooperative relation and the machine is not in operation. The 15 actual pressing action takes place at the final movement of the pressing head to exert pressure on the pressing bed as it has moved into cooperative relation therewith and it is at this period of the operation that the actual high pressure 20 is applied, the greater part of the movement of the head requiring only sufficient moving force to overcome the force exerted by springs or other means employed to return the head to its open unoperated position at the end of a pressing operation.

One object of my invention is to provide an operating mechanism for a pressing machine of the above type wherein the initial moving force for moving the head into cooperative relation with 30 the work supporting bed is relatively small and takes place only a comparatively short length of time yet the head of the press will be moved through the usual long arc about a pivot and be forced to its final position under a very high pressure. Thus, a quick operating press may be provided.

Another object of my invention is to provide an operating mechanism whereby the shortest stroke possible of the part which causes operation 40 or pressing engagement of the head with the bed will give the desired result and to make a simple and durable device which will permit economy of force required to produce the desired result.

The mechanism by which I attain the above mentioned and other objects of my invention consists, in this instance, of a very short arm or connection relative to the pivoted arm on which a pressing head is mounted and a very long arm, 50 both arms being integral parts of the arm carrying the pressing head and swinging about a common pivot. Initial movement of the part which causes pressing engagement of the head and bed, for instance, a pedal or a fluid pressure cylinder 55 and piston, acts on the pressing head through

the very short arm to move the head into cooperative relation with the pressing bed and the final movement of the part causing the pressing operation acts on the pressing head through the very long arm. That is, the movement of the operating 60 part is transferred from the very short arm to the very long arm during the time the movement of the pressing head is taking place.

Various other objects and advantageous features of my invention will be seen in the following description and one embodiment thereof may be seen in the accompanying drawings wherein similar characters of reference designate corresponding parts, and wherein:

Fig. 1 is a side view, partly in section, of a 70 pressing machine embodying my invention and showing the pressing head in open or unoperated position relative to the pressing bed; and Fig. 2 is a view similar to Fig. 1 but showing the pressing head in closed or operated position with relation to the pressing bed.

Referring to the drawings, I have shown one embodiment of my invention as comprising a buck 1, which, as usual, is rigidly secured to the top of a standard or frame 2 provided with rearwardly and upwardly extending supports 3 at the upper end of which is secured a cross shaft 4. A hub 5 having three radiating arms 6, 7 and 8 is pivotally mounted on the shaft 4, the arms 6 and 7 being bifurcated to avoid interference 85 with centrally located operating mechanism and to add rigidity thereto. The usual pressing head 9 is mounted on the extremity of the arm 6 in such position that the lower surfaces of the pressing head 9 will register with the top of the buck 90 1 when the head is in its lowered or closed position as shown in Fig. 2.

It will be noted that the arm 8 is substantially shorter than the arms 6 and 7 and is provided with a perforation or substantially vertically extending opening adjacent its outer extremity. Likewise, it will be noted that the arm 7 is substantially longer than either of the arms 6 or 8 and has a pair of links 10 pivotally connected to its free end as at 11. The free ends of the links 10 are, in turn, pivotally connected to the free end of an arm 12 as at 13 and the other end of the arm 12, is, in turn, pivotally connected as at 14 to the lower part of the frame 2. The arm 12 takes substantially the form of a bell crank and the short arm 15 thereof is connected to the frame 2 by means of a spring 16 whose tension may be adjusted by a nut 17 whereby the bell crank is normally maintained in the position shown in Fig. 1 to hold the pressing head 9 in open or un- 116

operated position as will be hereinafter described.

As will be clearly apparent, the links 10 form one-half of a toggle structure while the arm 12 forms the other half of the same toggle which is disposed between the frame 2 and the free end 5 of the relatively long arm 7. The arrangement of the parts is such that the toggle is in a substantially straight line between the pivot point 14 and the pivotal connection 11 when the pressing head 9 is tightly against the buck 1. Therefore, a small amount of pressure downwardly on the pivot 13 will cause a relatively great pressure downwardly on the buck 1 by the pressing head 9 as will be clearly seen in Fig. 2. This is due, 10 primarily, to the ratio of length of the arms 6 and 7.

The operating means for moving the pressing head 9 into engagement with the buck 1 and causing the pressing operation to take place, in this 15 instance, consists of a compressed air cylinder 18 that is rigidly secured to the upper portion of the frame 2 with its piston rod 19 extending downwardly. The lower end of the piston rod 19 is pivotally connected as at 20 to a bell crank lever 21 and the free end of the short arm of such bell 25 crank lever has pivotally connected thereto as at 22 the lower ends of duplicate links 23 whose upper ends are pivotally connected as at 24 to a rod 25 that passes upwardly through the per- 30 foration or opening adjacent the extremity of the short arm 8. Such rod 25 is provided with a head 26 some distance above the upper surfaces of the short arm 8 and a coiled expanding spring 27 is interposed between the head 26 and 35 the upper surface of the arm.

As shown in Figs. 1 and 2, the end of the longer arm of the bell crank lever 21 is so disposed and arranged as to contact with an extension 28 on the arm 12 and extending beyond the pivotal connection 13 between the arm 12 and the links 10. However, the lower end of the bell crank lever 21 only contacts with extension 28 on the arm 12 when the bell crank lever is in its lowermost moving position as shown in Fig. 2 due to 40 the fact that the lower end of the bell crank lever is guided outwardly on being moved downwardly by a cam surface 29 disposed on the frame 2. The spring 27, being under tension, exerts a constant pull upwardly on the links 23, which, being 45 connected to the short arm of the bell crank lever 21, will cause the free end of the long arm of the bell crank lever to be constantly forced against the cam surface 29.

In the operation of this apparatus, assuming 50 the pressing head 9 to be in opened or unoperated position as shown in Fig. 1, a garment is placed on the pressing bed 1 with the proper lay, a shield 30 being provided to prevent the garment from contacting with any of the operating mechanism, and air pressure is admitted to the cylinder 18 as by way of the conduit 31 by reason of opening a valve 32. Air pressure being admitted above the piston in the cylinder 18 will cause downward movement of the piston rod and the bell crank 55 21. Likewise, it will cause downward movement of the links 23 which, through the spring 27, will move the short arm 8 downwardly in an arc about its pivot and thus move the pressing head 9 down into engagement with the pressing bed 1. The length ratio between the short arm 8 and the arm 6 is such as to cause a large degree of movement of the head 9 with a small degree of movement of the arm 8.

Such downward movement of the pressing head 75 9 will result in an outward movement of the free

end of the arm 7 and a substantial straightening of the toggle mechanism made up of the links 10 and arm 12. This is clearly shown in Fig. 2. The downward movement of the piston rod 19 will also cause the free end of long arm of the bell crank 21 to be moved outwardly until it is in a position to contact with the extension 28 of the arm 12 that is brought under the long end of the bell crank lever arm by the substantial straightening of the toggle. This final pressure movement of the operating part will be transferred from the short arm 8 to the long arm 7. Then, the final downward movement of the piston rod 19 will be directly exerted through the bell crank lever 21 against the extension 28 of the arm 12 80 to force the toggle still nearer a straight line and thus exert a large amount of pressure in proportion to the downward force of the piston to the right against the free end of the long arm 7 which will, in turn, exert still greater pressure on the pressing bed or buck 1 by the pressing head 9 due to the ratio of the length of the arms 6 and 7. Obviously, as shown in Fig. 2, the spring 27 provides for the downward movement of the piston rod 19 to cause pressure between the head and bed 85 as hereinbefore described without breakage of parts. After the pressing operation, a valve 32 may be operated to permit pressure to be exhausted from above the piston in the cylinder 18 whereupon the toggle, arms and pressing head 9 will 90 be returned to their normal open or unoperated position by the spring 16 as will be readily apparent.

Referring to the drawings and the preceding description, it will be seen that I have provided 110 a machine embodying numerous novel and advantageous features. For instance, I have provided a pressing machine embodying operating mechanism such that the pressing head may be moved into cooperative relation with the pressing bed or buck by the expenditure of a small amount of energy together with a means for exerting a high pressure on the pressing bed or buck by the pressing head with the expenditure of a small amount of energy and movement 115 of the operating parts through a short distance. This is primarily accomplished by the use of a plurality of arms and links whose length ratio is such as to cause a large degree of movement of one arm or link by a relatively small movement 120 of another arm or link, or a system of arms and links wherein a small amount of energy and small degree of movement of one arm or link will cause a large amount of force to be exerted by an arm or link moved thereby. Thus, very little 125 energy need be expended to cause movement of the operating parts throughout a substantial distance and a high degree of pressure between the pressing elements, the last pressure being what is commonly termed as the final pressure or 130 "squeeze".

Another novel and advantageous feature of my invention resides in the fact that I have provided a pressing machine embodying the usual work receiving bed and a pressing head normally 140 in separated or full open position, and operating mechanism for moving the head into pressing relation with the bed and causing a final pressure or "squeeze" therebetween, consisting of a single motor means and associated mechanism for 145 moving the head into initial engagement with the bed and with such movement providing an operative connection between the single motor means and other associated parts for causing a final pressure or "squeeze" between the head and bed. 150

- Thus, it will be seen that I have provided a pressing machine in which a single motor means is effective to cause initial engagement of the pressing head and bed and then cause a final pressure or "squeeze" therebetween, the operation of the mechanism for causing the final pressure or "squeeze" being dependent on the operation of the mechanism for causing initial engagement of the head and bed.
10. What I claim is:
1. In a pressing machine embodying a work receiving bed and a pressing head normally in separated or full open position, operating mechanism including a single motor means and associated parts for moving said head into initial engagement with said bed, a toggle mechanism also associated with said head moving means, said toggle mechanism being normally ineffective as a head moving means, and means set by the operation of parts in moving said head to initial engagement with the head to provide a connection between said single motor means and said toggle mechanism whereby said toggle mechanism may be actuated by operation of said single motor means to cause further actuation of said head and produce a final pressure between said head and bed, said toggle being moved toward straight line position by movement of said parts to cause initial engagement of said head and bed and then further moved toward straight line position after said operative connection is made between said toggle mechanism and said power unit, said connection including a bell crank operatively connected to said single motor means and movable to make an operating connection between said single motor means and said toggle by operation of the parts to move said head into initial engagement with said bed.
  2. In a pressing machine embodying a work receiving bed and a pressing head normally in separated or full open position, operating mechanism for moving said head into pressing relation with said bed and for causing final pressure between said head and bed comprising a single motor means, a plurality of pivotally mounted integral arms including a head carrying arm and head moving arms of different lengths having their axis of movement about the same point, means for exerting force on the shorter of said head moving arms to cause initial engagement of said head and bed, and means for effecting an operative connection between the longer of said head moving arms and said motor means during movement of said head into initial engagement with said bed whereby said last named head moving arm may be actuated by said single motor means to cause final pressing pressure between said head and bed.
  3. In a pressing machine embodying a work receiving bed and a pressing head normally in separated or full open position, operating mechanism for moving said head into pressing relation with said bed and for causing a final pressing pressure between said head and bed comprising a single motor means, a plurality of pivotally mounted integral arms including a head carrying arm and head moving arms of different lengths having their axis of movement about the same point, one of said head moving arms being operatively connected with said motor means and another head moving arm normally having no operating connection with said power unit, means for exerting force on said first named head moving arm to cause initial engagement of said head and bed, and means for effecting an operative connection between the last named head moving arm and said motor means during movement of said head into initial engagement with said bed whereby said second named arm may be actuated by said single motor means to cause final pressing pressure between said head and bed.
  4. In a pressing machine, embodying a work receiving bed and a pressing head normally in separated or full open position, operating mechanism including a motor means directly connected with said head by a yielding connection for moving said head and bed into closed position, a toggle mechanism operatively connected to said head and being normally ineffective to move said head, and means set by the operation of parts in moving said head and bed to closed position to provide a connection between said motor means and said toggle mechanism whereby said toggle may be actuated by said motor means to produce pressing pressure between said head and bed.
  5. In a pressing machine embodying a work receiving bed and a pressing head normally in separated or full open position, said head being carried by a pivotally mounted arm, operating mechanism for moving said head and bed into closed position and for causing final pressure between said head and bed including a motor means, a plurality of head moving arms of different lengths operatively connected with said head carrying arm, a direct connection between the shorter of said head moving arms and said motor means whereby said motor means may be effective to move said head and bed to closed position, and means for effecting an operative connection between the longer of said head moving arms and said motor means by movement of said head and bed into closed position and operation of said motor means whereby said last named head moving arm may be actuated by said motor means to cause final pressure between said head and bed.
  6. In a pressing machine embodying a work receiving bed and a pressing head normally in separated or full open position, said head being carried by a pivotally mounted arm, operating mechanism for moving said head and bed into closed position and for causing final pressure between said head and bed including a motor means, a plurality of head moving arms of different lengths operatively connected with said head carrying arm, a direct yielding connection between the shorter of said head moving arms and said motor means whereby said motor means may be effective to move said head and bed to closed position, and means for effecting an operative connection between the longer of said head moving arms and said motor means by movement of said head and bed into closed position and operation of said motor means whereby said last named head moving arm may be actuated by said motor means to cause final pressure between said head and bed.
  7. In a press of the class described, the combination of coacting relatively movable pressing members and actuating mechanism therefor comprising, parts for closing the press, toggle mechanism associated with said parts, motor means and connections independent of any portion of the toggle for actuating said press closing parts, and means set by operation of said press closing parts to provide a connection between said motor means and said toggle mechanism, whereby said toggle mechanism may be actuated to apply final pressure.
  8. In a press of the class described the combination of coacting relatively movable pressing members and actuating mechanism therefor comprising, parts for closing the press, toggle mechanism associated with said parts, motor means and connections independent of any portion of the toggle for actuating said press closing parts, and means set by operation of said press closing parts to provide a connection between said motor means and said toggle mechanism, whereby said toggle mechanism may be actuated to apply final pressure.

nation of relatively movable pressing members, actuating mechanism for moving one of said members to closed position and for applying final pressure comprising, a lever connected with the 5 member, said lever having two arms rigidly connected therewith, a motor, means for applying power from said motor to one of said arms for closing the press, and means for applying power from said motor to the other of said arms for 10 applying final pressure.

9. In a press of the class described, the combi-

nation of relatively movable pressing members, actuating mechanism for moving one of said members to closed position and for applying final pressure comprising a lever connected with the member, said lever having a short arm and a 80 long arm rigidly connected therewith, a motor, means for applying power from said motor to the short arm for closing the press, and means for applying power from said motor to the long arm for applying final pressure.
